CLOTHING DISPLAY RACK

Daniel E. Gelles, Kerhonkson, N.Y.
(1140 Broadway, New York, N.Y. 10001)

Filed Nov. 13, 1967, Ser. No. 9,371

Term of patent 14 years

(Cl. D80—9)

FIG. 1

FIG. 2

The broken line representation of clothing supports in the three views is for purposes of illustration only.

I claim:

The ornamental design for a clothing display rack, substantially as shown and described.
